UNITED STATES PATENT OFFICE.

ARTHUR FREDERICK HAWKSLEY, OF ALTRINCHAM, ENGLAND.

CIGAR-LIGHTER.

SPECIFICATION forming part of Letters Patent No. 447,875, dated March 10, 1891.

Application filed January 29, 1890. Serial No. 338,467. (No model.) Patented in England September 1, 1886, No. 11,135.

To all whom it may concern:

Be it known that I, ARTHUR FREDERICK HAWKSLEY, a subject of the Queen of Great Britain and Ireland, residing at Altrincham, 5 in the county of Chester, England, have invented a new and useful Improvement in Cigar-Lighters, of which the following is a full, clear, and exact description. (Patented in Great Britain, No. 11,135, dated September 1, 10 1886.)

My invention relates to cigar-lighting apparatus or to means for lighting cigars, cigarettes, or tobacco in other forms, and principally to means for obtaining incandescent 15 heat, such as is obtained by the use of ordinary fusees.

The object of my invention is to provide the lighters in such a form as that they can be carried in compact cases or holders and be 20 projected therefrom singly for use. I make a case or fusee-holder of a form suitable to be carried in the waistcoat-pocket—as, for example, I may make such holder similar in form to a pencil-case of a hexagonal, round, 25 or square form in cross-section.

The ignitors, which for convenience of description I will term "fusees," consist of isolated masses of composition formed upon a thin rod or upon connecting material, so that 30 a rod to hold, say, a dozen (more or less) of such fusees can be placed within the holder. The holder is provided with a sliding pusher, whereby the end fusee can be caused to project from one end of the holder. The fusees 35 may be tipped on one side or be suitably prepared to be ignited by rubbing upon a prepared surface, as in the cases of ordinary safety-matches, or by simple friction, as in the cases of ordinary fusees.

40 My invention will be best understood when described with reference to the accompanying drawings, wherein—

Figure 1 is an outside view of the lighter-case closed, so as to be ready to be placed in 45 the pocket. Fig. 2 represents the same article with the cap removed and having a lighter projected from one end, and Fig. 3 represents the ignitors with which the case is charged.

In Fig. 1, *a* is a tubular case, and *b* is a cap, 50 which is slid upon the case and incloses about half of its length. In Fig. 2 the said cap is supposed to have been removed. The case *a*

is slit from end to end or thereabout, or is made by bending a piece of sheet metal into a tubular form, the edges of the metal not 55 quite meeting, so that a slit *c* is left between such edges. The case is partly inclosed within an outer case *d*, which extends from one end about half-way down the length of the inner case, and is also made with a slit to permit 60 the passage of the button *e*, which is attached to a pusher or piston *e'*, which slides within the case *a*. The outer case *d* may also be made by bending a piece of sheet metal into a tubular form. One end of the case is contracted, 65 so as to leave only a small opening or mouth, and in this end of the case a number of slits *ff* are formed and extend from the said mouth some distance or to varying distances, as in the indication. 70

In Fig. 3, *g* are the aforesaid isolated masses of composition, which are formed or fixed upon a rod of wood *h*, or it may be upon a shaft or core of other suitable material. The mouth at *f* is made large enough to pass this rod of 75 wood without extra expansion of the mouth.

In the manufacture of the said ignitors I make a paste similar to what is used in the manufacture of ordinary cigar-lighters and fill the same into molds, which are formed 80 with cells or cavities to receive the paste, and are adapted to hold a rod of wood or two or more rods in position to be surrounded by the masses of paste which are molded by the said cells. Each ignitor is tipped or coated on one 85 side with a suitable igniting composition. In some cases I coat or cover the cap-tube *b* with a composition, which is supposed to extend from *i* to *i*, and which is adapted to assist in the ignition of the lighters, as in the cases of 90 the coatings on ordinary safety-match boxes. In the molding of the ignitors it is important that the short lengths of wood which appear between every two ignitors shall be as free as conveniently possible from the composition. 95 Such a multiple ignitor as is represented by Fig. 3 is introduced into the case *a*, and the pusher is then put in at the end, a slight spring of the slit case keeping it in place. When a light is required, the cap *b* is removed 100 and the button *e* is pushed upward, so that the end ignitor is thrust out at the end of the case, as in Fig. 2, the slits in the case permitting the end of the case to expand and open

like a mouth and to close again behind the ignitor, so as to isolate it from the next adjacent ignitor in the series. The ignitor is then rubbed upon the cap or is otherwise ignited.

5 I do not confine myself to the precise formation or construction of the case, nor to the formation of it in two pieces *a* and *d*, nor to the provision of the cap *b*, so long as the case is made suitable to hold the ignitors and 10 to project the end ignitor by acting upon a sliding part.

Having now described the said invention, I declare that what I claim is—

In a cigar or pipe lighter, the separate masses of ignitable composition *g*, threaded or molded 15 in a series at distances apart upon a stick or core *h*, in combination with the case *a*, having slits *f* and the pusher *e*, substantially as set forth.

In witness whereof I have hereunto set my 20 hand in presence of two witnesses.

ARTHUR FREDERICK HAWKSLEY.
